UNITED STATES PATENT OFFICE.

DUNCAN JAMES McGAURAN, OF GERALDTON, WESTERN AUSTRALIA, AUSTRALIA.

TELEPHONE-CALL RECORDER.

1,135,971.

Specification of Letters Patent. Patented Apr. 13, 1915.

Application filed December 15, 1914. Serial No. 877,848.

To all whom it may concern:

Be it known that I, DUNCAN JAMES McGAURAN, a subject of the King of Great Britain, residing at Brede street, Geraldton, 5 in the State of Western Australia, Australia, have invented certain new and useful Improvements in and Relating to Telephone-Call Recorders, of which the following is a specification.

10 The invention relates to telephone call recorders and has been devised in order to provide means for preventing the recording mechanism being operated, until the calling subscriber has been in circuit for a predetermined time; the object being to insure only effective calls being registered.

15 The invention may be used in conjunction with instruments of the class described in my copending applications Serial Nos. 20 786220, 839933 and 839994 wherein broadly stated a timing mechanism is employed and automatically controlled by the exchange for throwing the call recording mechanism out of action for a predetermined time when the 25 exchange calls the subscriber.

According to my present invention when the subscriber makes a call on the exchange, his "switching in" to circuit releases a gear train set to run for a predetermined time at 30 the expiration of which the call will be recorded if the calling subscriber is then "in circuit." Should he however have returned his instrument to normal position before that time has elapsed, no call will be recorded against him.

Broadly stated, and in a particular form the device consists of a timing mechanism T. M. (Fig. 1) which is controlled from the exchange by the electromagnet X—a gear 40 train G. T. which is controlled by the movement of the subscriber's switch A; and the recording mechanism R. M. which is operated by the movement of the gear train lever C.

45 The accompanying drawings—Figures 1, 1^a and 2 are diagrams illustrating the invention, and the mode of operation is as follows:—

(1) The calling subscriber, wishing to call 50 the exchange, lifts the receiver R from the switch A (Fig. 1) which will then rise to the circuit contacts (in a manner well known in the art) carrying with it the arm B whose bifurcated end B¹ sits on lever C. Lever C 55 will be thereby released, and under the tension of the spring S will move over the arc

Z. Z¹ (indicated by studs) carrying with it the ratchet wheel W of the gear train G. T. with which it engages by the pawl piece D, the rate of motion being governed by the 60 gear train G. T. and fly F. The arm C¹ of the lever C carries the pawl piece E, which is adapted to engage with the ratchet wheel l of the recording mechanism R. M. Thus when lever C attains the limit of its travel, 65 the arm C¹ and pawl piece E will have moved over an arc of the ratchet wheel l and engaged the next tooth. Hence at the expiration of the predetermined time-limit, 70 as for instance 30 seconds, the lever C will have arrived at Z' turning wheel W and the arm C¹ with it and the pawl piece E will have engaged with the next tooth on the ratchet wheel l. At the close of the conversation 75 the subscriber will replace the receiver R on the switch A and the arm B will then bear on the lever C back to the stud Z and pawl E will move l and record a call. It is evident that should the subscriber have received the "engaged" or "cannot raise" 80 signal from the exchange and replaced his receiver R within the time limit the recording mechanism will not have been operated.

(2) The called subscriber: When the exchange calls a subscriber the calling ring 85 energizes the electromagnet X which is inserted in the calling circuit (in a manner well known in the art) and causes it to attract the armature J attached to spring controlled lever K, which moves about a pivot 90 L. This attraction of the lever K causes the arm M to disengage with the notched wheel N and release the timing mechanism T. M. It also moves the arm O, to engagement with the fly F of the gear train at the stud Q and 95 holds it in such engagement, for the predetermined period of time, as for instance, 30 seconds—when the next notch in the wheel N will have come into position, and M and K will resume their normal position. This 100 movement of the arm O also causes the stud U to take up such a position in respect to the beveled stud U¹ on lever T as shall permit the said stud to engage with the stud U, should the called subscriber answer the call, 105 during the running of the timing mechanism, in which event he will have removed his receiver R; his switch A and the arm B will rise as before described. The lever T being thus freed at T' will move on its pivot 110 and its stud U¹ will engage with stud U and hold the arm O so that the stud Q is held in

engagement with the fly F and prevents the running of the gear train and consequent recording movement of lever C. The lever K and arm M will have resumed their normal positions at the expiration of the predetermined time, but the stud Q will be kept in engagement with fly F as described until the close of the conversation when the replacing of receiver R on switch A causes the 10 arm B to bear on the end T' of the lever T thereby releasing the stud U¹ from engagement with the stud U which permits the arm O to regain its normal position.

In Fig. 1^a is shown a modification where- 15 by the recording mechanism is operated electrically instead of mechanically. The recording movement of the lever C, arm C' and pawl piece E as before described, causes the ratchet wheel 7 to momentarily close the 20 recording circuit at contact points 22 and 3. When the circuit is thus closed the electromagnet 5 will be energized by the current from battery 15, via the wire 9, the contact points 3 and 22, wire 4 electromagnet 5 the 25 wire 6. When so energized the electromagnet 5 will attract the armature 10 attached to the spring controlled armature lever 11 which carries the pawl piece 13 adapted to engage with the ratchet wheel 14 of the recording mechanism R. M. which will thus be 30 actuated.

The called subscriber:—When the exchange calls the subscriber the operation of the respective parts will be as described for

35 Fig. 1. The particular object of this modification of my recorder is primarily to allow a subscriber who is using a telephone installed on an automatic exchange system a reasonable time to manipulate the calling 40 apparatus and ascertain whether the line required is engaged or not. On such a system the subscriber puts himself "out of circuit" the moment he replaces his receiver on the hook switch and the selective device at the 45 exchange immediately falls back to its normal position.

It is apparent that on a central energy or magneto system, a subscriber may prevent the operation of the recording mechanism 50 by manipulating his receiver hook switch unless means are employed to prevent him doing so. To accomplish this an arrangement such for instance as that shown in Fig. 2 may be incorporated with the device for 55 use on a magneto system. With this arrangement the switch A is normally locked by the segmental toothed rack piece 1 attached to it, engaging with the locking piece 2 of the spring controlled armature lever 3. 60 A subscriber wishing to call the exchange operates his ringing apparatus thus energizing the electromagnet 4 which is inserted in the calling circuit (in a manner well known in the art). When so energized the 65 electromagnet 4 attracts the armature 5 of

armature lever 3, actuating it to engagement with the pivoted arm 6, by the pin 7 on lever 3 engaging with the indent 8. By this movement of lever 3 the locking piece 2 is disengaged from the rack piece 1 thereby unlocking the switch A which is then free to rise to the circuit contacts on the removal of the receiver. At the termination of its upward movement the switch A will engage with arm 6 depressing the indent 8 from engagement with the pin 7, thereby releasing lever 3 which returns to engagement with the rack piece at the locking piece 2. Should the subscriber now momentarily depress his switch with the object of preventing the lever C of Fig. 1 from attaining its full recording movement, the switch will be unable to again rise to its circuit contacts, on account of being locked at 1—2. Hence the subscriber will be unable to converse and will have to ring up again in order to unlock his switch. 70 75 80 85

The called subscriber:—When the exchange calls a subscriber the calling ring energizes the electromagnet 4 and the switch 90 is unlocked as set out.

Somewhat similar provisions may be incorporated with the device for use on a central energy system, but as any such manipulation by the subscriber would manifest 95 itself to the exchange officials by the alternate glowing and going out of the calling lamps, it is assumed to be unnecessary to particularize for such a contingency.

I claim:—

1. In telephone call recorders, the combination with the subscriber's switch of a gear train controlled by the movement of said switch and adapted to run for a predetermined time when subscriber switches in, a 105 recording mechanism operated through the medium of said gear train after the said predetermined time has expired, and a timing mechanism operated by a call from the exchange for rendering inoperative the recording 110 mechanisms.

2. In telephone call recorders, the combination with the subscriber's switch of a gear train a spring controlled lever for operating the same, said lever being released when said switch rises and a recording mechanism operated also by said lever after it has reached its limit of movement, and a timing mechanism operated by a call from the exchange for rendering inoperative the recording 115 120 mechanisms.

3. In telephone call recorders, the combination with the subscriber's switch of a gear train a spring controlled lever arranged to operate it for a predetermined time, an arm attached to said switch and normally holding said lever in inoperative position, said lever being released by the rising of said arm, stops governing the movements of the lever, an arm on said lever provided with a pawl 125 130

engaging a ratchet wheel in the gear of the recording mechanism, and a timing mechanism operated by a call from the exchange for rendering inoperative the recording mechanisms.

4. In telephone call recorders, the combination with the subscriber's switch of a gear train controlled by the movement of said switch and adapted to run for a predetermined time when said switch rises, a recording mechanism operated through the medium of said gear train after the said predetermined time has expired, a timing mechanism operated by the exchange, controlling means for stopping the gear train, and a lever operated by the telephone switch for releasing said controlling means.

5. In telephone call recorders, the combination with the subscriber's switch of a gear train controlled by the movement of said switch and adapted to run for a predetermined time when said switch rises, a recording mechanism operated through the medium of said gear train after the said predetermined time has expired, an electromagnet in the calling circuit, a timing mechanism adapted to be released for a predetermined time by said electromagnet, a wheel in said timing mechanism having notches at predetermined intervals, a lever attached to the armature of said electromagnet adapted to engage with the notches in said wheel, an arm operated by said lever, a stud on said arm adapted to arrest the gear train another stud on said arm adapted to engage with a stud on a lever controlled by said switch, and an arm connected with said switch adapted to bear upon said lever.

6. In telephone call recorders, the combination with the subscriber's switch of a gear train controlled by the movement of said switch and adapted to run for a predetermined time when said switch rises, a recording mechanism operated through the medium of said gear train after the said predetermined time has expired, a timing mechanism operated by a call from the exchange for rendering inoperative the recording mechanisms, means for locking said switch, and an electromagnet in the calling circuit adapted to release said locking means when subscriber or exchange calls.

7. In telephone call recorders, the combination with the subscriber's switch of a gear train controlled by the movement of said switch and adapted to run for a predetermined time when said switch rises, a recording mechanism operated through the medium of said gear train after the said predetermined time has expired, a timing mechanism operated by a call from the exchange for rendering

inoperative the recording mechanisms, a spring controlled armature lever, a toothed rack piece on said switch, a locking piece on said armature lever adapted to engage said rack piece, a pivoted arm above said switch formed with an indent adapted to be engaged by a pin on the lever, and an electromagnet in the calling circuit adapted to control said armature lever.

8. In telephone call recorders, the combination with the subscriber's switch of a gear train controlled by the movement of said switch and adapted to run for a predetermined time when said switch rises, a contact, an electrically operated recording mechanism controlled by said contact made at the limit of the forward movement of the gear train, and a timing mechanism operated by a call from the exchange for rendering inoperative the recording mechanisms.

9. In telephone call recorders, the combination with the subscriber's switch, of an arm attached to said switch, a gear train, a spring controlled lever adapted to be released by the rising of said arm, stops governing the movements of said lever, an arm on said lever and a pawl on said arm, a ratchet wheel engaged by said pawl, an electrically controlled recording mechanism, a circuit including said mechanism, said ratchet wheel when moved closing said circuit, and a timing mechanism operated by a call from the exchange for rendering the said recording mechanism inoperative.

10. In telephone call recorders, the combination with the subscriber's switch, of an arm attached to said switch, a gear train controlled by said arm, a spring controlled lever adapted to be released by the rising of said arm to operate for a predetermined time said gear train, stops governing the movements of said lever, an arm on said lever, a pawl on said arm, a ratchet wheel engaged by said pawl, an electromagnet, an electric circuit including said electromagnet, a contact in said circuit, said ratchet wheel, when moved, adapted to close said contact, a call recording mechanism, a ratchet wheel therein, a spring-controlled armature lever operated by said electromagnet, a pawl on said lever in engagement with said ratchet wheel, and a timing mechanism, operated by a call from exchange for rendering said recording mechanism inoperative.

In testimony whereof I have hereunto set my hand in presence of two subscribing witnesses.
